ORTHO PSEUDO STEREO RANGE FINDER

Stephen M. MacNeill, Oak Ridge, Tenn., assignor to Eastman Kodak Company, Rochester, N. Y., a corporation of New Jersey

Application July 6, 1945, Serial No. 603,496

8 Claims. (Cl. 88—2.7)

1

This invention relates to ortho-pseudo stereoscopic range finders. Such range finders are described in two of the earlier cases of this series namely, Serial No. 479,101, Mihalyi and MacNeill, filed March 13, 1943, now U. S. Patent 2,401,710, and Serial No. 526,020, MacNeill, filed March 11, 1944, now U. S. Patent 2,403,732.

It is the object of the present invention to provide an ortho-pseudo stereo range finder in which sources of error are minimized by having the beam combining system unitary in form. It is the specific object of one embodiment of the invention to provide an invert field ortho-pseudo stereo range finder. The advantages of ortho-pseudo systems over ordinary stereoscopic range finders and over coincidence type range finders are well known. The purpose of the present invention is to provide an arrangement which can be manufactured with great accuracy and which is capable of maintaining this accuracy even when incorporated into a long base range finder such as those used for height finders.

The present invention employs polarizing beam splitters. A Nicol prism can be arranged to act as a polarizing beam splitter and various other simple forms are known. However the most valuable form of polarizing beam splitter, especially for the present purpose is that described in my copending application, Serial No. 481,391, filed April 1, 1943, now U. S. Patent 2,403,731. In that copending application a polarizing beam splitter is made up of alternate layers of materials of high and low indices of refraction, each having an effective optical thickness at Brewster's angle of one-quarter wavelength to give constructive interference to the reflected rays. Six such layers are equivalent in polarizing power to 148 parallel glass plates separated by air.

According to the present invention an ortho-pseudo stereo range finder having the usual spaced viewing points, binocular viewing means and image forming means is characterized by a polarizing beam splitter positioned to receive light from each of the viewing points and to divide it into two beams polarized at right angles which for convenience may be referred to as a first beam and a second beam. The first beam from one beam splitter and the second beam from the other beam splitter are then combined to form superimposed or juxtaposed images in the image plane of one of the eyepieces. Similarly the other beams form images in the image plane of the other eyepiece. Preferably each of the beam splitters also acts as a beam combiner for receiving the second beam from the other beam splitter and combin-

ing it with its own first beam. For example, the second beams may be the transmitted ones and, for the sake of symmetry, these may be arranged to pass through a half wave retardation plate or the equivalent to rotate the plane of polarization through 90 degrees before striking the other beam splitter whereat they are reflected.

To provide an invert field, means are included in one of the beams from each beam splitter for inverting the image relative to the image formed by the other beam.

In those embodiments of the present invention in which right and left viewing point images are formed optically ahead of the central prism assembly including the polarizing beam splitters, the simplest way of providing juxtaposition of the images is to mask off half of each of these primary images. Thus the first beam from each of the beam splitters forms an image in one-half of the respective eyepiece image plane and due to inversion, the image formed by the second beam in each case exactly covers the other half of the eyepiece image plane.

Instead of thus masking half of the primary image plane, and in those cases where there is no primary image ahead of the central prism assembly, the juxtaposed image arrangement may be obtained very simply due to the fact that the two images reaching each image plane are polarized at right angles. This alternative employs a polarizing filter with two sections polarized at right angles for transmitting respectively the first and second beams reaching the image plane. This embodiment has the added advantage that the dividing line of the juxtaposed images depends only on the accuracy with which the filter is made and not at all on the relative setting of other optical elements.

Various specific embodiments of the invention and their relative advantages will be understood from the following detailed description when read in connection with the accompanying drawings, in which:

Figs. 1, 4, 5, and 6 are perspective views of optical systems of slightly different embodiments of the invention all incorporating the same central prism assembly.

Fig. 2 is a plan view of the central prism assembly employed in Figs. 1 to 6.

Fig. 3 shows the binocular field of view in an ortho-pseudo stereo range finder.

Figs. 7 and 8 are respectively a perspective view and a plan view of a slightly different central prism assembly which may be used in Figs. 1 to 5.

Fig. 9 is a perspective view of an optical system

according to another embodiment of the invention.

Fig. 10 is a plan view of the central prism assembly used in Fig. 9.

Fig. 11 is a front elevation of the same central prism assembly.

Fig. 12 is a perspective view of the optical system of still another embodiment of the invention.

Figs. 13 and 14 are respectively front and side elevations of the central prism assembly shown in Fig. 12.

In Fig. 1 light from a target being ranged is received at spaced viewing points by penta reflectors or optical squares 20 and directed through objectives 21 which form target images in primary image planes 22. The lower half of each plane is masked off by an opaque area 23. Preferably the image planes 22 include field lenses as shown. The images thus formed are relayed by relay lenses 24 through a central prism assembly to eyepiece image planes 35.

The central prism assembly receives the beam from the observer's left hand viewing point through one side face of a prism 25. The hypotenuse face of this prism is cemented to polarizing beam splitter 26 so that the reflected beam is polarized at right angles to the transmitted beam. The reflected beam passes from the prism 25 at normal incidence through an entrance face 34 into a complex prism having two plane reflecting surfaces 27 and 34 (reflecting at greater than the critical angle) and a roof surface 28 which reflects this beam through a half wave retardation plate 29 whereby the plane of polarization of the beam is rotated through 90°. The surface 27 is preferably metallized since the light strikes this surface at less than critical incidence.

The right viewing point image similarly enters a prism 30 and is split by a polarizing beam splitter 31. Again the reflected beam traverses the half wave retardation plate 29, is reflected by the roof prism 28 and plane surfaces 34 and 27 into prism 25.

The path of the beams is most clearly illustrated in Fig. 2. The rays of light are shown by broken lines and are purposely selected slightly off-axis so as to distinguish between the two incoming beams and particularly between the four outgoing beams. In other words the rays shown do not represent the axial ray of the beams.

Since the plane of polarization of the reflected beam from each beam splitter has been rotated through 90° these beams will be transmitted respectively by the other beam splitter and pass through directly to the image planes 35 of the eyepieces 37 to permit binocular viewing of the images by the right and left eyes 38 and 39 of the observer. The portion of the left viewing point beam which is transmitted by the beam splitter 26 and similarly the portion of the right viewing point beam which is transmitted by the beam splitter 31 pass through quarter wave retardation plates 33 and are reflected by a total reflector 32 sandwiched between the quarter wave plates so that the beams each traverse the quarter wave plates twice, thus rotating their plane of polarization through 90°. After this reflection and rotation of the plane of polarization, the beams are reflected by the polarizing beam splitters 26 and 31 and are combined respectively with the beams from the other viewing points as they pass through to the image planes 35. Due to the roof or dihedral reflector 28, the two images in each image plane are inverted relative to one another and due to the masks 23, these images

are juxtaposed. This is shown in Fig. 3 wherein the left viewing point image in the left eyepiece image plane and the right viewing point image in the right eyepiece viewing plane are shown at 40. The left viewing point image in the right eyepiece image plane and the right viewing point image in the left eyepiece image plane are shown at 41. The dividing lines 43 between the images 40 and 41 correspond to the edges of the masks 23 located in the primary image planes. As shown, the erect images 40 would appear stereoscopically nearer than the invert images 41. Adjusting means 44 is provided in one of the range finder beams for deviating the light and for ranging in the usual way.

Fig. 4 differs from Fig. 1 by having all of the image forming system optically after the central beam splitting and combining prism assembly. This has a very valuable advantage since once the beams are combined for ortho-pseudo viewing the optical elements which act thereon are no longer critical since they act simultaneously and equally on both beams. In Fig. 4 light is received at spaced viewing points by penta prisms 50 and 51 and passed directly to the same central prism assembly as shown in Fig. 1, one of the beams passing through a light deviator 46. After beam splitting and combining one pair of beams is focussed by an objective 52 in the right eyepiece image plane and the other pair of beams is focussed by an objective 53 in the left eyepiece image plane. The two images in each image plane are superimposed, one inverted relative to the other and they are polarized at right angles. In each image plane there is located a polarizing filter 54 having two sections 55 and 56 polarized at right angles as indicated by the double-headed arrows adjacent to each section. Thus the sections of the images transmitted to the eyepieces are juxtaposed again as in Fig. 3.

Fig. 5 is similar to Fig. 4 but includes a system of mirrors for making that portion of the optical system which follows the central prism assembly more compact. The combined beams from each side of the central prism assembly are reflected by front surface reflectors 60 respectively through image forming lenses 61 and 62 which correspond to the objectives 52 and 53 of Fig. 4. The beams are then each twice reflected by mirrors 63 back to image planes 64 after which they are again each reflected by mirrors 65 to eyepieces 37.

Fig. 6 is a practical compromise between the arrangements shown in Figs. 1, 4, and 5. The objectives 70 are optically ahead of the combining prism, but there is no primary image ahead of the prism since the images formed by the objective 70 are in the eyepiece image planes 71. This has the advantage of the arrangement shown in Fig. 1 in that the eyepieces are located quite close to the central prism assembly without the elaborate mirror system of Fig. 5. It has part of the advantage of Fig. 4 to the extent that only the objectives are ahead of the beam splitting and combining prism.

The central prism assembly shown in Figs. 7 and 8 can replace that shown in Figs. 1 to 6 in any of the embodiments so far described. The left and right viewing point beams enter prisms 75 and 77 respectively and are beam split by polarizing beam splitters 76 and 78 respectively. The transmitted beams in this case however, pass straight through to strike the other beam splitter whereat they are reflected since the plane of polarization of these transmitted beams are rotated through 90° by a half wave retardation

plate 79. Each of the reflected rays as they first strike the beam splitters 76 and 78 pass through quarter wave retardation plates 80 to strike triple mirrors 81 whereat they are reflected and completely inverted. They then pass again through the quarter wave retardation plates 80 so that on re-entering the prisms 75 and 77 respectively they are able to pass through the beam splitters 76 and 78 to be combined with the rays reflected therefrom to the eyepiece. The orientation of the triple mirrors (best visualized as the corner of a cube) is not at all critical. They are shown with one side parallel to the entrance faces of the prisms 75 and 77, the edge being cut off leaving the surface 85 in each case. Similarly the top corners have been cut off leaving surfaces 84 level with the prisms 75 and 77 and again the inside corners have been cut away leaving surfaces 83. It will be noted that small areas 82 of the quarter wave retardation plates 80 are not covered by the triple mirror and the system may be slightly inefficient due to this; but if the system is objectionable for this reason, larger triple mirrors may be used with the edges and corners cut away as in the present case.

Fig. 9 shows a preferred embodiment of the invention in which one of the viewing point penta prisms 90 is located effectively below and in front of the base of the range finder and the other viewing point penta prism 91 is located above and slightly behind this base line. Actually of course this off-setting is very slight and the equivalent effect is obtained by proper orienting of the penta reflectors in a symmetrical appearing housing. The right viewing point light beam enters a Porro prism 92 and is deflected from the first reflecting surface thereof to a polarizing beam splitter 93 located on the other reflecting surface of the prism. Similarly the left viewing point beam enters a Porro prism 96 and is reflected to a polarizing beam splitter 97. The two Porro prisms 92 and 96 are oriented at right angles to each other so that the beams reflected from the beam splitters 93 and 97 are directed toward each other and because of the relative orientation of the beam splitters, these reflected beams pass respectively through the other beam splitters to the objectives 100. Those portions of the original beams transmitted by the beam splitters 93 and 97 respectively strike quarter wave retardation layers 94 and 98 and are reflected respectively by reflecting layers 95 and 99 back through the quarter wave retardation layers which results in the plane of polarization being rotated through 90°. These rays are then reflected by the beam splitters 93 and 97 and are combined with the rays which have been first reflected and then transmitted by the beam splitters. The light from the lenses 100 is reflected by mirrors 101 and comes to focus in the image planes 102 in each of which a polarizing filter with two sections polarized at right angles is located. The light from the image planes is reflected by mirrors 103 through eyepieces 104 to the eyes 105. It will be noted particularly from the similarity of the plan and elevation views in Figs. 10 and 11 that the light beams travel symmetrical paths.

The embodiment shown in Fig. 12 has the right viewing point penta prism 110 effectively behind the base of the range finder and the left viewing point penta prism 111 effectively in front of the base. The right and left viewing point beams enter prisms 115 and 116 to strike polarizing beam splitters 117 and 118 respectively. As shown in

Fig. 13 these polarizing beam splitters are at right angles to one another and located one behind the other. In each case the transmitted beam passes through a quarter wave retardation layer 120 and is reflected by a mirror 121 back to the beam splitters. These beams are then reflected downward by the beam splitters respectively through objectives 125 and 126. The other half of each viewing point beam is reflected upward by the beam splitters 117 and 118 to a Porro prism 127 wherein they cross and are reflected downward to the other beam splitter respectively. A half wave retardation layer 128 rotates the plane of polarization of both of these second portions of the light beams so that they are oriented to pass through the beam splitters and to be combined with the first portions as reflected therefrom. The combined beams pass through the lenses 125 and 126 striking mirrors 130 so that they are directed into the image planes 131 of eyepieces 132. As before, each image plane contains a polarizing filter with sections polarized at right angles.

Having thus described various embodiments of my invention I wish to point out that it is not limited to these structures but has the scope of the appended claims.

I claim:

1. An ortho-pseudo stereoscopic range finder having spaced viewing points for receiving light from the target being ranged, two eyepieces for binocular viewing and means for directing light from each viewing point to form two images of the target being ranged in the image plane of each eyepiece, characterized by a polarizing beam splitter positioned to receive light from each viewing point and to divide it into a first and second beam polarized at right angles, means for directing to one eyepiece image plane the first beam from one beam splitter and the second beam from the other beam splitter, said directing means including a plurality of reflecting surfaces and each beam splitter acting as a beam combiner, combining its first beam with the second beam from the other beam splitter, a reflector positioned in each of the second means to reflect them respectively back to the beam splitters and means included in said second beams to intercept each of them twice for rotating the plane of polarization through 90°.
2. A range finder according to claim 1 in which means for inverting the image is included in one of the beams from each beam splitter.
3. A range finder according to claim 1 including means for forming a target image between each viewing point and the corresponding beam splitter which receives light from that viewing point, means for relaying the image through the beam splitter, beam combiner system to the eyepiece image planes and a mask covering one-half of each of the images between the viewing points and the corresponding beam splitter.
4. A range finder according to claim 1 including in each of the eyepiece image planes a polarizing filter with two sections polarized at right angles for transmitting respectively the first and second beams reaching that image plane.
5. An ortho-pseudo stereoscopic range finder having spaced viewing points for receiving light beams from the target being ranged, two eyepieces for binocularly viewing images of the target and means for forming in the image plane of each eyepiece two target images by light respectively from the two viewing points characterized by a central prism assembly including a polarizing beam splitter positioned to receive light from each

viewing point respectively and to form a first beam and a second beam polarized at right angles, the first beam in each case being reflected by the beam splitter, a plane reflector and a roof reflector for reflecting each of said first beams respectively to the other beam splitter, a half wave plate for rotating the plane of polarization intercepting said first beams so that each of the first beams will be transmitted by said other beam splitter, the second beams in each case being transmitted by the beam splitters, a quarter wave retardation plate and a total reflector for receiving each of said second beams, for reflecting them back respectively toward their beam splitters and for rotating their plane of polarization through 90 degrees whereby they are reflected from the beam splitters and combined with the second beams being transmitted by the beam splitters.

6. A range finder according to claim 5 including in each of the eyepiece image planes a polarizing filter with two sections polarized at right angles for transmitting respectively the first and second beams reaching that image plane.

7. An ortho-pseudo stereoscopic range finder having spaced viewing points for receiving light beams from the target being ranged, two eyepieces for binocularly viewing images of the target and means for forming in the image plane of each eyepiece two target images by light respectively from the two viewing points characterized by a central prism assembly including a polarizing beam splitter for receiving light from each viewing point, and for splitting it into a first reflected beam and a second transmitted beam polarized at right angles, a quarter wave retardation plate and a triple mirror for receiving each of the first beams, for rotating their plane of polarization through 90 degrees and for reflecting them back to and through the beam splitter, a half wave retardation plate intercepting each of the second beams for rotating their plane of polarization through 90 degrees and for transmitting them respectively to the other beam splitter

for reflection thereat and for combining with the transmitted first beam in each case.

8. An ortho-pseudo stereoscopic range finder having spaced viewing points for receiving light beams from the target being ranged, two eyepieces for binocularly viewing images of the target and means for forming in the image plane of each eyepiece two target images by light respectively from the two viewing points characterized by a central prism assembly including a Porro prism for receiving light from each viewing point and for reflecting it once from the first reflecting surface of the Porro prism to the second reflecting surface thereof, a polarizing beam splitter at the second reflecting surface for splitting each beam into a first reflected beam and a second transmitted beam, the Porro prisms being oriented at right angles to each other to reflect the first beams toward each other and through the other beam splitter in each case, a quarter wave retardation plate and a reflector positioned to receive each of the second beams, to rotate their plane of polarization through 90 degrees and to reflect them back to the respective beam splitters whereat they are reflected and combined with the transmitted first beams and means for directing each pair of first and second beams respectively to the eyepiece image planes.
